A. H. KENNEDY

MATHEMATICAL APPARATUS

Original Filed Feb. 18, 1921

INVENTOR.

A. H. Kennedy.

UNITED STATES PATENT OFFICE.

ALBERT H. KENNEDY, OF ROCKPORT, INDIANA.

MATHEMATICAL APPARATUS.

Application filed February 18, 1921, Serial No. 446,112. Renewed June 11, 1923.

To all whom it may concern:

Be it known that I, ALBERT H. KENNEDY, a citizen of the United States, a resident of Rockport, in the county of Spencer and State of Indiana, have invented a new and improved mathematical apparatus for the purpose of generating an infinite number of right-angled triangles upon a common hypotenuse, together with squares upon the other two sides, making in all positions complete and exact diagrams of the Pythagorean proposition.

I attain this object by means of the mechanism illustrated in the accompanying drawing, which shows its plan and operation.

In the present position of the mechanism, 1—2—3 represents a right angled triangle, 1—4—5—2 represents the square upon the hypotenuse, 1—3—7—6 represents the square upon the longer leg and 2—3—8—9 represents the square upon the shorter leg.

The lines in the figure represent wires, bars of steel, brass, or any other rigid material.

The bars about the square 1—4—5—2, are made rigid at the corners, so that it may retain its shape.

The two bars 1—10 and 1—14 are fastened rigidly together at right angles and are pivoted at 1.

The two bars 2—15 and 2—13 are likewise fastened rigidly together at right angles and are pivoted at 2. The bars 15—13, 10—15 and 10—13—14 hold these two systems at right angles to each other in any possible position, as they are rotated about the points, 1 and 2. The bars 10—15, 1—2 and 13—14 are all equal to each other. 16 and 17 are the corners of the square 1—2—17—16.

The bar 6—12 is pivoted at 16 and kept parallel to 1—14 by the connecting bar 12—14 which is equal to 1—16.

Likewise the bar 9—11 is pivoted at 17 and kept parallel to 2—7 by the connecting bar 11—15 which is equal to 2—17.

The bars 12—14 and 11—15 are each equal to the bar 1—16.

It is obvious that in this manner the two pairs of hinged parallelograms 1—2—13—14, 1—14—12—16 and 1—2—15—10, 2—17—11—15 are thus connected into one system

at right angles to each other and that as the system is rotated to the right or left on the pivots 1—2—17—16, they will remain at right angles to each other in any and every position, the bars intersecting at 3 always being perpendicular to each other.

It will also be noticed that 1—2—3 is a right angled triangle in any and every position and has squares generated upon its two legs while the square upon the hypotenuse remains constant.

It will also be noticed that as the system is rotated toward the right, the square 1—6—7—3 grows larger and larger as the square 2—3—8—9 grows smaller and smaller until it disappears and the square 1—6—7—3 becomes equal to 1—2—5—4, the square upon the hypotenuse.

In like manner, when the system is rotated toward the left the reverse becomes true.

The members of this system of parallelograms may be extended below, so as to rotate about the four corners of the square 1—16—17—2, but the results would be the same. Also the parallelograms may be extended below and be connected with additional parallel members as above, but it would be in all respects identical with the plans and functions above described. Whether the square on the hypotenuse is below it, as shown by 1—2—5—4, or above it, as shown by 1—16—17—2, makes no difference in the plan or the functions performed.

I claim as my invention:

1. The combination of two pairs of hinged parallelograms, pivoted at the four corners of a square and connected and functioning in such a manner that when rotated about these four points, the two pairs of parallelograms will remain at right angles to each other in all possible positions, substantially as described.

2. The combination of two pairs of hinged parallelograms, pivoted at the four corners of a square, so connected and functioning, that when rotated about the four points, they will generate right angled triangles in all possible positions, with one side of the said square as a common hypotenuse, substantially as set forth.

3. The combination of two pairs of hinged parallelograms, pivoted at the four corners of a square, and so connected and functioning, that when rotated about these four points, they will generate in all possible positions two squares upon the legs of a right angle triangle, whose hypotenuse is equal

to one side of the said square, substantially as described.

A. H. KENNEDY.
